SLACK CONTROLLER

Ward W. Stewart, Girard, Ohio

Application August 3, 1944, Serial No. 547,889

2 Claims. (Cl. 188—197)

1

This invention relates to slack controllers used in connection with brake mechanisms of railway cars.

The principal object of the invention is the provision of a slack controlling device for use with the brake operating mechanisms of railway cars.

A further object of the invention is the provision of a slack controller that may be employed with railway car brakes for adjusting the slack existing in the brake mechanisms and which is capable of several methods of attachment to the railway cars with respect to the brake mechanism.

A still further object of the invention is the provision of a slack controller that is simple in construction, inexpensive to manufacture and efficient in operation.

A still further object of the invention is the provision of a slack controller for a railway car brake mechanism providing means for automatically slackening off the brake mechanism after being manually set.

The slack controller shown and described herein has been designed to form a simple and efficient mechanism which may be easily constructed and readily applied to railway cars in connection with the brake mechanisms of such cars, and which may be applied and efficiently used in several different applications in connection with such brake mechanisms, such as, for example, a draft sill application wherein the slack controller is attached directly to the dead link of the brake mechanism. An alternate positioning is in the center sill application wherein the slack controller is attached to the floating lever of the brake mechanism and a still further application possible is a center sill application wherein the slack controller is attached to the brake rods. In any one of these applications the slack controller shown and described herein accomplishes the dual purpose of providing a convenient and efficient slack adjusting means and at the same time provides for the automatic slackening off of the brake mechanism from the manual setting made thereby insuring against the brake mechanism being set too tight which would cause undue wear in the brake shoes and other portions of the brake mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

2

The invention is illustrated in the accompanying drawing, wherein:

Figure 1 is a plan view of a slack controller in position on the center sill section of a railway car.

Figure 2 is an enlarged cross sectional elevation of a portion of the slack controller illustrated in Figure 1.

Figure 3 is a cross sectional side elevation taken on lines 3—3 of Figure 2.

Figure 4 is a diagrammatic illustration showing the slack controller in draft sill application.

Figure 5 is a plan view of the slack controller in a center sill application.

Figure 6 is a plan view of the slack controller in center sill application attached to and forming a part of the brake rods.

By referring to Figures 1, 2 and 3 in particular it will be observed that a slack controller has been illustrated which takes the form of a bar 10 having a plurality of teeth 11 formed on the upper surface thereof and provided with a handle 12 at one end and with an opening 13 at the other end to enable the bar 10 to be attached directly to the brake mechanism of a railway car, for example, to a dead link 14 of such brake mechanism. The bar 10 is supported at one end by the brake mechanism, as illustrated in Figure 1, by the link 14 and the other end of the bar 10 is

adjustably positioned in a U-shaped bracket 15 which is provided with an out-turned flange 16 on one of its upturned arms. The out-turned flange 16 serves as a means of mounting the U-shaped bracket 15 as best illustrated in Figure 2. By referring to Figures 1, 2, 3 and 4 of the drawing it will be observed that a plurality of suitable fasteners such as rivets 17 are employed to mount the bracket 15 beneath the draft sill 18 of a railway car. The U-shaped mounting bracket 15 which supports the toothed rod 10 is provided with a pair of semi-L-shaped slots 19 in the upturned arms thereof and these semi-L-shaped slots 19 are adapted to operably receive a roller pin 20 which is held therein in a movable manner by

means of a washer 21 and cotter pin 22 (see Figure 2). The roller pin 20 in transverse position in the bracket 15 extends through the slots 19 and is provided on one end with a head 20A so that while it can move in the slots 19 it cannot escape therefrom. In such position the roller pin 20 forms an adjustable connection between the bracket 15 and the bar 10 as it is adapted to engage the spaces between the teeth 11 so as to hold the bar 10 in desirable adjustment. It will

be observed that the near vertical portions of

the semi-L-shaped slots 19 in the brackets 15 incline to the left as illustrated in Figures 1, 3 and 4, and that these slots 19 are of sufficient height to permit the roller bar 20 to rise above the uppermost edge of the teeth 11 on the bar 10 when the bar 10 is drawn to the left, as illustrated in Figures 1, 3 and 4, as by manipulation of the handle 12. When this occurs the roller pin 20 will automatically reset in each of the spaces between the teeth 11 when the bar 10 is moved to adjust the slack in the brake mechanism. When no further movement is applied to the bar 10 the brake mechanism normally urges the bar 10 to the right, as illustrated in Figures 1, 3 and 4, and thereby moves the roller pin 20 into the horizontally positioned portions of the slots 19 in the brackets 15 in which position the roller 20 remains, it being observed that the horizontal travel possible provides for the slackening off of the brake mechanism from the manual setting made as the bar 10 is permitted to travel to the right a distance comparable with the length of the horizontal section of the slots 19, moving the roller pin 20 in so doing. It will thus be seen that the construction illustrated and described provides for the convenient manual adjustment of the slack in the brake mechanism and also provides for the slackening off from the manual setting made thereby insuring against the possibility of the brake mechanism being adjusted too tightly.

By referring to Figure 4 of the drawing it will be observed that the adjustment made with the slack controlling mechanism is directly applied to the brake mechanism through the lever 14 and that such adjustment directly effects the positioning of the brakes themselves.

As set forth in the objects of the invention the slack controller shown and described herein is capable of mounting on attachment to the brake mechanism of a railway car in locations other than the draft sill application heretofore described and illustrated in Figures 1, 2, 3 and 4.

In Figure 5 of the drawing an alternate center sill application is illustrated wherein the slack controller is illustrated as consisting of a toothed bar 23 provided with a handle 24 on one end and a slot-like opening 25. The toothed bar 23 is positioned beneath a center sill 26 by means of a bracket 27 similar in all respects to the bracket 15 heretofore described in connection with Figures 1, 2 and 3 of the drawing. The slot-like opening 25 near the one end of the toothed bar 23 provides for the attachment thereto of the brake mechanism which includes the floating lever and which mechanism is generally indicated by the numeral 33. It will thus be seen that in such a center sill application wherein attachment is made to the floating lever of the brake mechanism the slack controller operates effectively in that the same adjustment and slackening off features heretofore described are utilized in adjusting the slack in the brake mechanism and providing for the slackening off from the adjusted position.

By referring now to Figure 6 a still further variation in the manner of formation and application of the slack controller to a brake mechanism may be seen wherein a toothed bar 27 is shown provided with a depending handle 28 and positioned through a supporting bracket 34 and partially held by an adjustment bracket 30 having a pair of semi-L-shaped slots 31 formed therein for the reception of a roller pin 32 adapted

to engage the space between the teeth on the bar 27. The device illustrated in Figure 6 differs from that illustrated in Figures 1 through 5 of the drawing and heretofore described in that the semi-L-shaped slots 31 are formed in the adjustment bracket 30 which is directly attached to and preferably forms a part of the brake rod mechanism 29A, the entire device thereby comprising an adjustable linkage between the brake rods 29 and 29A and capable of effective use in controlling the slack in the brake mechanism to which the brake rods 29 and 29A are attached.

In all of the applications disclosed and illustrated herein it will be observed that the novel principle of adjustment and slack control is possible as is the automatic slackening off feature provided for by the positioning of the roller pins 20 or 32 in the semi-L-shaped slots 19 or 31. It will thus be seen that the slack controller consists of a rather simple mechanism which can obviously be inexpensively manufactured, easily applied to railway cars in connection with the brake mechanisms thereof and that it forms an effective and trouble free slack controller providing for the ready manual slack adjustment and the automatic slackening off of that adjustment to a desirable degree. It is also obvious that the slack controller may be readily inspected and its operation easily checked as there are no housings or other structural members to interfere with the inspection of the device and its manual manipulation.

Having thus described my invention, what I claim is:

1. In a slack controller for railway brake mechanism, a bracket adapted for connection with a fixed support, a pair of semi-L-shaped slots formed in said bracket and a toothed bar connected with the said brake mechanism and positioned through the said bracket, a roller pin positioned through the said slots and engageable with the said toothed bar, the said slots in the said bracket permitting the said roller to rise and disengage the said bar when the said bar is moved in one direction and when said bar is moved a predetermined distance in the other direction, the said slots permit the said roller to drop into engagement with the said bar and thereby hold the said bar from further movement in that direction.

2. Brake operating means including a brake rod and a lever for operating the same, a slack controlling device in connection therewith, said slack controlling device including a bracket having a toothed bar slidably engaged therein, means in said bracket for engaging the said toothed bar, said means permitting the said toothed bar to be moved freely in one direction and to slack off and hold the said bar against movement in the opposite direction, the said means comprising a pair of semi-L-shaped slots formed in the said bracket and a roller pin positioned therethrough in operable engagement with the said toothed bar, the near vertical portion of the said semi-L-shaped slots being of a height sufficient to permit the roller pin to move over the said toothed bar when the said bar is moved in one direction and the horizontal portion of the semi-L-shaped slots being of a length sufficient to provide for the slackening off of the toothed bar prior to engaging the same when the said toothed bar is moved in the opposite direction.
